[57] CLAIM

The ornamental design for an riflescope cover, as shown and described.

DESCRIPTION

FIG. 1 is a right side elevational view of a riflescope cover, showing my new design, the left side being a mirror image thereof;

FIG. 2 is a top plan view, the bottom being a mirror image thereof;

FIG. 3 is a front elevational view thereof;

FIG. 4 is a rear elevational view thereof; and,

FIG. 5 is a side elevational view, partially broken away and partially in cross-section.

FIG. 1

FIG. 2

FIG. 3

FIG. 4

FIG. 5
